UNITED STATES PATENT OFFICE.

JAMES SARGENT, OF ROCHESTER, NEW YORK.

GAME-TALLY.

SPECIFICATION forming part of Letters Patent No. 245,873, dated August 16, 1881.

Application filed May 31, 1881. (No model.)

To all whom it may concern:

Be it known that I, JAMES SARGENT, of Rochester, Monroe county, New York, have invented a certain new and useful Improvement 5 in Game Counters and Tallies; and I do hereby declare that the following is a full, clear, and exact description of the same, reference being had to the accompanying drawings, in which—

10 Figure 1 is a plan of the device. Fig. 2 is a vertical cross-section in line $x x$. Fig. 3 is a plan of the lower disk removed from place. Fig. 4 is a section of Fig. 3 in line $y y$. Fig. 5 is an elevation, partially in section, of one of 15 the pins.

My improvement relates to game counters and tallies in which a case is used having sliding pins which pull up, but not out, to register the game.

20 The invention consists in the construction and arrangement hereinafter more fully described.

In the drawings, A represents a sheet-metal case, which is spun, stamped, swaged, or otherwise formed in proper shape. It consists, substantially, of a rim which forms the body, being open at bottom and top, but having at the top 25 an interior flange, which forms a shoulder, a , and having also at some distance below the top a second shoulder, b , which is formed by 30 pressing or stamping out in the rim. Near the bottom is also a third shoulder, c , formed in the same manner as the last named.

B and C are two thin, flat metallic disks of 35 just the right size to fit within the case and rest closely up against the two shoulders a b , and are fastened in place by soldering or otherwise, leaving an open space, d , between them, as shown in the sectional view, Fig. 2. The 40 upper disk, B, forms the top of the case, being, however, preferably covered with a pad of velvet or other fabric to present a good appearance. In the two disks B C are formed four rows of coincident holes, $f f$ and $g g$, two rows 45 on each side of the central line, as shown in Fig. 3. The lower disk, C, has also at intervals a series of larger holes, $h h$, for a purpose presently to be described. The two disks may be connected at intervals by rivets whose 50 heads $r r$ rest above the top of the upper disk

and present an ornamental appearance, as shown in Fig. 1.

$i i$ and $k k$ are four sets of headed pins, which rest in the coincident holes $f f$ $g g$ of the disks, being inserted from the under side and projecting above the upper disk. These pins slide up and down freely, but do not pull out. They are square-ended at the bottom, but are bored or reamed out at their lower ends, leaving a hollow or concave, l , Fig. 5, and the extreme 60 outer edges are turned out, forming a burr, m , which makes a shoulder that strikes the bottom of the lower disk as the pin is elevated and prevents it from drawing out. By thus forming the pins great simplicity and cheapness are secured, and vertical space for the movement of the pins up and down is saved over what would be required where the ends of the pins are flattened or otherwise formed to prevent them from drawing out. The concave in the end of the pins and the burr at the edge can be formed with a single tool, and at 65 one and the same operation. The pins are packed to produce the necessary friction to hold them at any adjustment by means of fibrous 70 material—such as cotton or wool—which is inserted through the large holes $h h$, filling the space between the two disks and surrounding the pins. The fiber is very elastic, and when once inserted it will allow great ease of motion 75 of the pins, and yet will always retain them when raised, being much more effective in these respects than thin sheets of rubber, paper, or other similar packings, which have but slight hold upon the pins and soon wear so that the 80 pins will slip.

D is a disk, of iron, lead, or other material, which forms a weight, inserted in the bottom of the case against the shoulder c , and secured in place by turning the lower edge of the rim 90 of the case inward under it. This is done after the pins have been inserted in place and the packing applied, as before described. The bottom of the weight may be covered by a paper or other soft pad to prevent scratching or marking of the furniture upon which the device is placed.

The device above described serves the double purpose of a counter—that is, an indicator of the number of points made by each party in a 100

single game—and as a register to indicate the number of games won by each party, so that a glance will show the condition of the playing. Each of the parties playing has two of the 5 rows of pins i k , the row i being for the purpose of registering the points in a single game, and the row k being for registering the number of games won. To register, the pins are simply raised, as shown at the left in Fig. 2.

10 Having thus described my invention, I do not claim sliding pins in a game-board; but

I claim—

15 1. In a game counter and tally, the combination of the case A and the two separate disks B C, secured within the case with a space between them, and provided with four rows of coincident holes, ff g g , for the reception of four rows of pins, as shown and described, and for the purpose specified.

20 2. In a game counter and tally, the combination of the case A, the two separate disks B C, secured within the case with a space between them, and a fibrous packing resting in the space and surrounding the pins, as herein 25 shown and described.

3. In a game counter and tally, the disk C, constructed with a series of holes, f g , to receive sliding pins, and with holes h h to allow the insertion of packing around the pins after the pins have been located, as herein shown 30 and described.

4. In a game counter and tally, the pin having a square lower end with a concave, l , formed therein, and a burr, m , thrown out at the outer edge of the pin to form a shoulder, 35 as herein shown and described.

5. In a game counter and tally, the combination of a spun, struck-up, or swaged case and sets of pins located therein, said case having bearings for the pins to rest in, and having 40 a bottom plate, D, located at such distance below as to allow proper sliding movement of the pins, as described.

In witness whereof I have hereunto signed my name in the presence of two subscribing 45 witnesses.

JAMES SARGENT.
